UNITED STATES PATENT OFFICE.

EMIL FRANKE, OF ASTORIA, NEW YORK

ELECTRIC BRAKE.

No. 857,729.

Specification of Letters Patent.

Patented June 25, 1907.

Application filed August 4, 1906. Serial No. 329,200.

To all whom it may concern:

Be it known that I, EMIL FRANKE, a citizen of the United States, residing at Astoria, in the county of Queens and State of New York, have invented new and useful Improvements in Electric Brakes, of which the following is a specification.

My invention relates to brakes for cars and more particularly to that class which utilizes the electric current which when turned from the motor may be utilized to operate the switch and may be economically and compactly located beneath the flooring of a car as will be more fully described in the following specification, the appended claims and the accompanying drawings in which:

Figure 1 represents a view of the bottom of a car showing my improved brake applied thereto. Fig. 2 is a longitudinal sectional view of the brake with its wiring. Fig. 3 is a side view of the device with its controller. Fig. 4 is a plan view of the controller handle and its stops.

This device is adapted to operate any form of brake but in order to show its application, a brake bar 5 of simple construction and having shoes 6 on their outer ends and operating in the slide 7, are connected by means of the links 8 with the levers 9 pivoted at 10 to the bottom of the car. The free ends of these levers 9 have secured to them rods 11 which are connected to cross-heads 12 and 12' the latter having at its outer ends horizontal rods 13 carrying tubes 14 in which play the rods 15 that are carried by the outer ends of the head 12, these rods thus telescoping so that the heads can approach each other so as to operate the brake beams 5 so that the shoes may work upon the wheels of the car. The rods 13 and 15 are adjustable on their respective heads and may be lengthened or shortened by means of the nuts 16 and 17. The tube 14 is slotted as at 18 so that the rods 15 may have secured to them by means of bolts 19, the cross-heads 20 which carry an armature 21. The tube 14 itself has secured to it a cross-head 22 with an armature 23. The cross-heads 12 and 12' carrying armatures 24 and 25 and these various armatures are influenced by the two separate and distinct cores 26 and 26' of the electro-magnets 27 and 28.

The electro-magnets are energized simultaneously by the circuit which will be herein-after described, and when energized the mag-

net 27 attracts the armature 21 connected with the cross-head 12 and the armature 24 on said cross-head is attracted by the magnet 28. Likewise the armature 21 on the cross-head 20 is attracted toward the magnet 27 while the same magnet attracts the armature on the cross-head 12' consequently drawing the rods 11 toward each other and operating the brake beams 5 so as to apply the brake.

The brake is operated by means of a magnetic circuit which may be a loop from the regular operating circuit and is controlled by means of the switch arm 30 which is adapted to make contact with the various resistance coils 31 so as to apply more or less current to operate the brake. The two lines 33 and 34 are not only adapted to supply the current to the electro-magnets but are also connected with a controlling switch at the other end of the car and which is a duplication of the switch 30. The current to the brake being supplied by the circuit 32 shown diagrammatically in Fig. 2 and whose course of power 35 may be a battery or dynamo. Blowout fuses 36 may be used at various points in the circuit and various expedients resorted to to apply the current in a practical manner.

The operation of the brake is as follows: When the current is supplied by means of the arm 30 by the closing of the contact points of the resistance coils 31, the electro-magnets are energized and the armatures are attracted toward the cores, the armatures 21 and 25 although connected with different cross-heads are attracted by the core 26' while the armatures 23 and 24 are attracted by the core 26. The rods 13 and 15 are adapted to slide one within the other so that they may find a bearing upon each other and the armatures working on the adjacent ends of the cores may work uniformly and in unison. The magnets are inclosed within a barrel or cylinder 37 in which are slots 38 and in each play the cross-heads 20 and 22. This cylinder is provided with ears 39 which guide the rods 13 and 15.

It is obvious that various modifications may be resorted to to accomplish the results without departing from the essential features of the invention as above described and illustrated.

The shaft carrying the controller arm 30 is carried within a tube 40 which is braced against the front platform of the car and has

at its top a perforated segment 41 having as many perforations 42 as there are resistance coils 31 and contact points 43 for these coils. The upper end of the shaft is provided with a handle and arm 44, the latter having a depending pin 45 which enters one of the holes 42 and determines which one of the points 43 the arm 30 is in contact with and holds the arm thereon.

10. What I claim as new and desire to secure by Letters Patent is:

1. In an electric brake for cars and vehicles the combination with a cylinder carrying electro-magnets, of a circuit including the 15 electro-magnets, one or more controllers in the circuit, cross-heads carrying armatures and telescoping within each other, brake beams and shoes and means connecting the cross-heads with the brake beams.

20. 2. In an electric brake for cars and vehicles the combination with a cylinder carrying two or more electro-magnets of cross-heads without the cylinder and carrying armatures, cross-heads within the cylinder and also carrying armatures, coupling means for the interior and exterior cross-heads, brake beams and shoes and means connecting the cross-heads with the brake beams.

30. 3. In an electric brake for cars and vehicles the combination with a casing inclosing two or more electro-magnets, cross-heads within and without the casing carrying armatures, telescoping connections for the cross-heads and adapted to allow the movement of two or more sets of cross-heads and move in the proper direction when the electro-magnets are energized, brake beams and 35 shoes and means connecting the cross-heads with the brake beams so that the brakes may 40 be applied.

4. In an electric brake for cars and vehicles the combination with two or more electro-magnets, of an electric circuit and controller, cross-heads with armatures adapted to be attracted by each end of the magnetic 45 core, coupling rods adapted to connect those cross-heads which move in corresponding directions when the magnets are energized, brake beams and shoes and connections between the brake beams and the co-operating 50 cross-heads.

5. In an electric brake for cars and vehicles the combination with electro-magnets in an electric circuit, of armatures coupled so as to work in the same direction when the magnets are energized, telescopic rods adapted to 55 carry the armatures and permit them to move in the same line, brake beams and shoes and levers and rods connecting each pair of correspondingly moving armatures 60 with the brake beams.

6. In an electric brake the combination with an electric circuit, of electro-magnets, armatures operated by each end of the magnetic cores, brake beams, means connecting 65 each brake beam so that it is operated by the correspondingly moving armatures, resistance coils in the circuit, a shaft carrying a contact arm for the coils, an operating handle and arm on the shaft with a depending 70 pin, a tube or sleeve carrying the shaft and a segment at the top of the sleeve with holes for the depending pin and corresponding in number with the resistance coils.

In testimony whereof, I affix my signature 75 in presence of two witnesses.

EMIL FRANKE.
